UNITED STATES PATENT OFFICE.

FANNIE C. LARIMER, OF LOS ANGELES, CALIFORNIA.

CLASP FOR FLEXIBLE FABRICS.

SPECIFICATION forming part of Letters Patent No. 642,236, dated January 30, 1900.

Application filed March 26, 1897. Serial No. 629,422. (No model.)

To all whom it may concern:

Be it known that I, FANNIE C. LARIMER, a citizen of the United States, residing at Los Angeles, in the county of Los Angeles and 5 State of California, have invented a new and useful Clasp for Flexible Fabrics, of which the following is a specification.

The object of this invention is to provide a very cheap, simple, and convenient clasp 10 which will be suitable for fastening flexible fabrics together or to ironing-boards and other fixed supports. The device is suitable for such use, for example, as to fasten children's covering to cribs or bed-frames and also as a 15 clasp for stocking and skirt supporters.

One advantage designed to be gained by my invention is to provide a clasp which is especially adapted to be easily fastened to ironing-boards to serve as a clasp for ironing-board 20 covers and which will not be in the way and will not be liable to catch and hold or tear fabrics being ironed and which will not be liable to become unclasped accidentally, but which will be very easy to clasp and unclasp both 25 tightly-drawn and loose fabrics indiscriminately.

One object is to form the entire clasp of but two single integral parts, which can each be formed by stamping. I do away with all necessary of assembling and riveting parts to 30 form the clasp.

Another object is to make provision for easily releasing the clasp.

My invention comprises a clasp composed 35 of two trough-shaped members contracted and outwardly flanged at their mouths and nested together, one or both of said members being resilient. Each of the members has a curved cross-sectional contour contracted at the base 40 and is provided at the base with a laterally-projecting attaching-flange at one or both sides of the base, and the other member is a trough-shaped spring approximately fitting the base, but leaving sufficient space between 45 the two to accommodate the fabric to be clamped.

My invention includes the several parts constructed substantially as herein set forth, reference being had to the accompanying drawings, which illustrate my invention.

Figure 1 is a perspective view of my clasp as applied to an ironing-board, a fragment of

which is shown with a portion of the ironing-board cover clasped in place. Fig. 2 is a cross-section through the hole 5. Fig. 3 is a detail 55 showing the members of the clasp separate and the inside or base member provided with points integral with the attaching projections. Fig. 4 shows the appliance arranged for use as a skirt-supporter. Fig. 5 is a longitudinal 60 section of a clasp made slightly tapering. Line 5, Fig. 2, shows the line of section.

A indicates a sheet-metal trough-shaped member with lateral base-flanges a a' , one or both having suitable means—such as the holes 65 or slots 1 or points 2, for fastening the same to a strap, a garment, or ironing-board or other support.

B indicates a spring sheet-metal trough approximately fitting upon the inner or base 70 member A and provided with lateral wings b b' .

In practical use on an ironing-board the base member A is fastened to the ironing-board or other support by suitable means, such as the points 2 or by tacks 3, driven through the 75 holes in the base-flanges. A sufficient number of these bases are placed along the opposite edges of the under side of the ironing-board D to hold the cover E.

To clasp the cloth or cover, the cloth is first 80 placed on the body portion of the base, (marked A in the drawings,) and then the trough B is sprung into place over the cloth and body of the base. The trough B is of such size in relation to the body of the base 85 that its edges will extend into the recess or depressions 4 between the swell of the body and the flanges a a' , but will leave sufficient space between the edges or wings b b' of the trough and the base-flanges a a' to accommodate the fabric which is to be clamped in place without 90 springing the jaws or sides of the trough apart so much as to loosen the hold of the lips of the trough on the fabric. The wings b b' are curved outward, so as to readily receive and slide over 95 the rounded portion of the base member A. The two members of the clasp are outwardly flanged, as at a a' a'' a''' b b' b'' b''' , to afford means for handling and fastening the members. The cloth will be fastened first at one 100 edge and will then be drawn tight over the ironing-board and clamped by the clamps on the other edge.

The clamp can be easily released by sliding

the trough along the tube of the base and thus off from such tube. The two members may be made slightly tapering, as indicated in Fig. 5, so that when started the other member can be readily slid off. The lateral wings *b* of the trough *B* serve as handles for this purpose; but for greater convenience and ease of removal I provide a thumb-nail hole 5 in the bottom of the trough *B*, so that the 10 user can insert the thumb-nail or any suitable instrument in the hole, and thus slide the trough off. This hole, being in the bottom of the trough midway between the opposite edges, causes the force in removing the 15 trough to slide the trough off without canting the trough, and thereby causing any undue friction.

The clasp can be used to fasten two flexible parts together and can also be used as a 20 hose-supporter or a skirt-supporter, a fold of the garment being clasped in between the two members. In the form shown in Fig. 4 the base or inner member *A'* has a wide flange *a''* and a narrower flange or wing *a'''*, the wide 25 flange *a''* being provided with a slot *l* for a strap *F*. The other flange *a'''* prevents the outer member *B'* from twisting on the body of *A'*, and thus releasing the clasped fabric. The trough-shaped member *B'* is provided 30 with a slotted flange *b''* and strap *F'*, being passed through the slot *l'* in such flange, thus forming a desirable clasp for a dress or stocking-supporter.

In practical use the sizes of different clasps will vary according to various uses for which 35 they may be designed. For a hose-supporter a quarter of an inch in diameter and a half-inch in length will be suitable. The outer member may be made to fit the inner member more or less loosely, according to the 40 thickness of the fabric to be clamped.

Now, having described my invention, what I claim as new, and desire to secure by Letters Patent, is—

1. A clasp composed of two trough-shaped 45 members, one of which has a curved cross-sectional contour contracted at the mouth of the trough, and having one limb provided at the mouth of the trough with a lateral attaching-flange; and the other of which members 50 is a trough-shaped spring substantially fitting the first-mentioned member above said flange substantially as set forth.

2. A clasp for fabrics comprising two integral resilient trough-shaped members of 55 curved cross-sectional contour contracted at the mouths of the trough and there provided with laterally-projecting attaching-flanges and being of such size relative to each other as to leave a sufficient space between the two 60 members to accommodate the fabric to be clamped substantially as set forth.

FANNIE C LARIMER.
